REFILLABLE BOOK

William L. Kennedy, Yeadon, Pa.

Application June 1, 1939, Serial No. 276,791

9 Claims. (Cl. 281—34)

This invention relates to refillable books, that is to say, note or check books of the type in which the leaves are removable from the cover and replaceable.

5 My invention is concerned with structural refinements in books of the kind referred to which make possible the quick removal and replacement of the leaf fillers; which effectively insure against the displacement of the leaf filler within
10 the cover notwithstanding careless handling of the books; and which, moreover, permit the leaves to lie perfectly flat when the books are opened

Other objects and advantages will appear from the following detailed description of the attached drawings, wherein

Fig. I is a fragmentary longitudinal edge view of a refillable book conveniently embodying my invention, opened and with a portion thereof broken out and shown in section.

20 Fig. II is a fragmentary view in plan of the open book, likewise with portions broken out and shown in section.

Fig. III is a fragmentary view generally like Fig. I, but with the book closed.

25 Fig. IV is a view in turn like Fig. III with one of the cover wings thrown open.

Fig. V is a fragmentary view in perspective of the cover of the book.

Fig. VII is a fragmentary detail view of the leaf inner of the book.

filler in longitudinal section; and Fig. VIII is a detail plan section of the filler taken as indicated by the angled arrows VIII-VIII in Fig. VII.

35 VIII in Fig. VII.
As herein shown, my improved refillable book
consists of a cover which is comprehensively des-
ignated by the numeral 1 and separately illus-
trated in Fig. V, and a filler which is compre-
40 hensively designated by the numeral 2 and sep-
arately illustrated in Fig. VI.

The cover 1, it will be observed, has a back 3 centrally between opposite cover wings 4 and 5 which are integrally united with said back through flexible connecting portions at 6 and 7. The cover wings 4 and 5 are formed with pockets 8 and 9 which are open toward the cover back 3 as shown in Fig. V, and provided with closure flaps 10 and 11 respectively capable of being retracted to render the pockets accessible for a purpose later on explained. As a convenient releasable means for normally holding down the flaps 10 and 11, I utilize snap fasteners of which the socketed buttons 12 and 13 are secured to the flaps, and the complementary studs 14 and 15 to the cover wings 8 and 9 respectively. Permanently attached to the inside of the cover back 3 by one or more clips such as shown at 16 in Figs. I, III, IV and V, is a reinforcing member 17 which is fashioned to channel section from

stiff sheet material, preferably metal. The parallel side flanges of said member 17 constitute inward ridge projections which are transversely notched at intervals as at 18.

As herein illustrated, the filler 2 (Fig. VI) includes a pack 20 of leaves with offset notches 21 along one of its short edges in which flexible retainers 22 are lodged. These retainers 22 may be of textile cord as shown in Figs. VII and VIII. Applied to the notched edge of the leaf pack 20 is a coextensive elastic adhesive strip 23. The retainers 22 and the strip 23 cooperate to effectively hold the leaves of the pack 20 assembled as a unit. The leaves are in this instance perforated along a transverse line 24 and also along parallel longitudinal lines 25 which intersect with said transverse line, and are thus subdivided into stubs 26 and check or receipt blanks 27. The pack 20 is, moreover, provided at the top and bottom with auxiliary backing sheets 28 and 29 of relatively stiff material which correspond in area to the stubs 26 and which are intended to serve as covers for the stubs 26 when the check blanks 27 have all been used. Other types of fillers may of course be provided in which the leaves are plain, ruled or otherwise subdivided and the backing sheets 28 and 29 made coextensive in area with the leaves of the pack. As shown, the backing sheets 28 and 29 are glued fast to the outermost leaves of the pack 20 along margins adjacent the bound edge of the latter as indicated conventionally at 30 and 31 in Fig. VII, and over the ends of the retainers 22. As another alternative, the filler may be composed of a pile of loose leaves without the notches 21. In any case, the leaves are provided somewhat inward of one edge with elongated apertures 32, which are spaced to correspond to the spacing of the notches 18 in the flanges of the stiffening member 17 on the cover 1.

Incorporated with the filler 2 is a binding element 33 fashioned from relatively tough flexible sheet material such for example as Celluloid or the like, having laterally extending tongues or straps 34 passed through the apertures 32 of the leaf pack 20. The strap-connecting bar portion of the element 33 is loosely lodged between the folds of a keeper strip 35 whereof the coincident edges are united by adhesive shown at 36 in Fig. VI, the tongues or straps 34 of said element extending outward through slits in one of said folds. For a purpose also later on described, the bar of the element 33 and the keeper strip 35 are provided at their centers with openings 33a and 37 respectively. The outer ends of the straps 34 of the binding element 33 are lodged between the folds of another keeper strip 38, and pairs of them at opposite ends of the series are secured by means of wire staples 39 to one of the folds of said strip, which fold is slotted, also as 40

shown in Fig. VI for passage of said straps. Co-
inciding edge margins of the keeper strip 38 are
united by adhesive as conventionally indicated at
40 in Fig. VI; and said strip provided centrally
5 with an opening 41.

The manner of assembling the book is as fol-
lows:

The cover 1 is opened and laid flat with the
10 pocket flaps 10 and 11 unbuttoned and thrown
back as in Fig. V. The filler component 2 is
then applied and the anchorage strips 35 and
38 inserted into the pockets 8 and 9 of the cover
15 wings 4 and 5, the bound edge of the leaf pack
20 being incidentally placed into the channel
hollow of the member 17 and the straps 34 en-
gaged at the regions of their emergence from
the pack, within the notches 18 of said mem-
ber. The pocket flaps 10 and 11 are thereupon
25 swung down to closed position and secured by
the snap fasteners 12, 14 and 13, 15, of which
the center ones respectively connect through the
openings 33a and 37 in the element 33 and strip
35, and through the opening 41 in the strip 38
to anchor the filler as best shown in Figs. III and
30 IV. In this connection, it is to be noted that
the buttons and studs of the endmost snap fas-
teners interengage beyond the end strips 35 and
38 as shown in Fig. II.

It is to be furthermore noted from Figs. II, III,
35 and IV that the openings 33a and 37 in the bind-
ing element 33 and keeper strip are amply large to
permit the straps 34 to reeve back and forth
through the slits of said strip as the book is
opened and closed. As a consequence of this and
40 due to the flexibility of the retainers 22 and the
elastic strip 23, which connect the leaves of the
pack 28, the book will lie perfectly flat when
open as shown in Fig. I, which is particularly
advantageous with check books in that it facili-
45 tates filling out of the check stubs.

Preferably, the filler is made up for the market
as shown in Fig. VI completely assembled with
the binding element 33 and the keeper strips 35
and 38, and the intention is that said element
45 and strips be detached and discarded upon ex-
haustion of the check blanks and removal of the
stub pack from the cover 1.

The invention is of course not to be regarded
as limited to the precise details of construction
50 herein shown by way of example since, as will be
readily understood by those familiar with the art,
these are susceptible to considerable variation
within the scope of the broader of the appended
claims and as necessitated by the prior art.

Having thus described my invention, I claim:

1. A refillable book of the character described
comprising a filler including a pile of leaves which
have spaced apertures adjacent one edge, and a
plurality of binding straps passing through the
60 apertures of the leaves with their ends project-
ing; and a cover having a back centrally located
between opposite cover wings, pockets at the insides
of said wings open toward the cover back and
adapted to respectively receive the projecting ends
65 of the straps, and an inwardly extending stiffen-
ing member secured to the back and affording a
transversely notched ridge for engaging the straps
at the regions of their emergence from the pack
to prevent the latter from shifting up and down
70 in the cover.

2. A refillable book according to claim 1, in-
cluding means for releasably securing the strap
ends within one of the pockets only.

3. A refillable book according to claim 1, where-
75 in the notched ridges on the cover component

are provided by a channel section stiffening mem-
ber which is affixed to the cover back, which
receives the strapped edge of the filler within its
hollow, and which has its side flanges notched
for engaging the straps at the region of their
emergence from the pack to prevent the latter
from shifting up and down in the cover.

4. A refillable book according to claim 1, wherein
in the pockets on the wings of the cover are
10 formed with flaps which are retractable for con-
venience of inserting the strap ends; and wherein
in releasable means normally hold the flaps in
closed position over the ends of the straps.

5. A refillable book of the character described
comprising a filler including a pile of leaves with 15
spaced apertures adjacent one edge, a binding
element of flexible sheet material with lateral
tongue straps which pass through the apertures
of the leaf pile, the strap connecting portion
of said element being provided with an opening; 20
and a cover having a back centrally between op-
posite cover wings, pockets at the insides of said
wings open toward the cover back and adapted
to respectively receive the tongue ends and the
strap connecting portion of the binding element, 25
and a releasable means on the cover passing
through the opening in the strap connecting portion
of said element to secure the filler to the
cover, with the ends of the straps free to reeve
back and forth as the book is opened and closed. 30

6. A refillable book according to claim 5, wherein
in the releasable means is in the form of a snap
fastener which connects the walls of the pocket
occupied by the strap-connecting portion of the
binding element. 35

7. A refillable book comprising a filler includ-
ing a pile of leaves with spaced apertures adja-
cent one edge, and a plurality of binding straps
40 passing through the apertures of the leaves with
their ends projecting, and doubled keeper strips
within which the projecting ends of the straps are
lodged, having slits in which said straps may
reeve incident to opening and closing of the book;
and a cover having a back centrally located be-
45 tween opposing cover wings, and pockets at the
inside of the wings open toward the cover back
and adapted to respectively receive and hold the
keeper strips of the filler. 50

8. A refillable book of the character described
comprising a filler including a pile of leaves with
spaced apertures adjacent one edge, and a plu-
rality of binding straps passing through the aper-
tures of the leaf pile with their ends projecting,
45 and doubled keeper strips within which the pro-
jecting ends of the straps are lodged, having
slits in which said straps may reeve incident to
opening and closing of the book; and a cover
having a back centrally located between opposing
50 cover wings, pockets at the insides of the wings
open toward the cover back and adapted to re-
spectively receive and hold the keeper strips of
the filler, said pockets being formed with flaps
which are retractable for convenience of insert-
ing the keeper strips; and means for releasably
55 securing the flaps. 60

9. A refillable book according to claim 8, wherein
in the keeper strips of the filler are respectively
provided with openings; and wherein the releasable
securing means for the pocket flaps of the
cover component are in the form of snap fas-
teners certain of which pass through the open-
ings in the keeper strips to detachably anchor
70 the filler. 70
